United States Patent Office.

ALMON COOK, OF HILLSDALE, MICHIGAN. *

Letters Patent No. 89,384, dated April 27, 1869.

IMPROVED APPARATUS FOR SWAGING AND WELDING TOE-CALKS TO HORSE-SHOES.

The Schedule referred to in these Letters Patent and making part of the same.

To all whom it may concern:

Be it known that I, ALMON COOK, of Hillsdale, in the county of Hillsdale, and State of Michigan, have invented a new and improved Machine for Toeing Horse-Shoes; and I do hereby declare the following to be a full, clear, and exact description thereof, which will enable others skilled in the art to make and use the same, reference being had to the accompanying drawings, forming a part of this specification, in which—

Figure 1 is a transverse vertical section of my improved machine in the line $x x$, fig. 2; and

Figure 2, a front elevation of the same, partly in section, to show the construction of the mould.

Similar letters of reference indicate corresponding parts.

This invention has for its object to provide a machine by which the toe-calk of horse-shoes can be shaped and welded to the shoe-plate in the most accurate and expeditious manner; and

The invention consists in the construction of the mould for shaping the toe-calks, and in the combination therewith of the devices by which the calk is welded to the shoe.

In the drawings—

A is an upright frame or post firmly secured to the bed-plate B; and

C is a drop or pressure-bar sliding in guides D, affixed to, or formed upon the front of the upright A.

The drop is operated by a lever, E, having its fulcrum at a in the upper end of the drop, and with its short arm pivoted to the upper end of an upright, G.

H is a bar or holder, by which the horse-shoe is held against the base of the upright A during the process of welding.

This holder moves in suitable guides transversely of the bed-plate, and is operated by means of the bent lever I, having its fulcrum in the arm b projecting from the edge of the bed-plate B.

One arm of this lever is pivoted to the outer end of the holder, and its other arm extending beneath

the bed-plate, is attached, in any suitable manner, to the lower end of a rod or bar, J, which passes longitudinally through the upright A, and is secured at its upper end to the drop, as shown at e , fig. 1.

K is the mould, in the form of a horse-shoe toe-calk formed in the bed-plate at the base of the upright A, and in line with the drop and holder.

If preferred, it may be made of a separate piece of metal and let into the bed-plate, in which case it can be easily removed when desired.

The operation is as follows:

The horse-shoe blank having the toe-calk slightly affixed to it in the usual manner, and heated to a welding-heat, is placed upon the bed-plate with the toe-calk in the mould and with its ends extending upon each side of the holder. The lever E is then operated to bring the drop down upon the shoe, for the purpose of welding the calk to same, and at the same time shaping the latter by forcing it into the mould K.

The holder H prevents the metal from being spread laterally to widen the shoe under the blows of the drop.

$d d$ are perforations in the bed-plate B to permit the escape of air from the mould during the process of welding.

By means of my improved machine, the toe-calks can be welded to horse-shoes in the most expeditious manner and with great economy of labor.

Having thus described my invention,

What I claim as new, and desire to secure by Letters Patent, is—

The combination of the drop C and holder H with the mould K, all arranged and operating as described, for the purpose of welding the toe-calk to a horse-shoe, and shaping the same at one operation, substantially as herein shown and described.

ALMON COOK.
